UNITED STATES PATENT OFFICE.

LEVI B. BULLINGTON, OF DEXTER, KANSAS.

FLUID AND OIL BURNER.

No. 856,334.

Specification of Letters Patent.

Patented June 11, 1907.

Application filed April 2, 1907. Serial No. 365,919.

To all whom it may concern:

Be it known that I, LEVI B. BULLINGTON, a citizen of the United States, residing at Dexter, in the county of Cowley and State of 5 Kansas, have invented certain new and useful Improvements in Fluid and Oil Burners, of which the following is a specification.

This invention is a burner for vaporized liquid fuel, and has for its object to provide 10 improved means for commencing and continuing the vaporization of the fuel.

The burner is particularly adapted for the combustion of crude petroleum, although other hydro-carbons may be used if desired.

15 The invention is illustrated in the accompanying drawing, which is a side elevation, partly in section, of the apparatus.

Referring specifically to the drawing, 6 indicates the tank or source of supply for the 20 oil. A pipe 7 leads from the tank to the burner, and is provided with a controlling valve 8. The end of the pipe at the burner is turned or presented upwardly, and it supports a primary generating pan 9 which extends around the same. Above the pan the 25 pipe is branched to the form of a T, the branches being indicated at 10, projecting from the pipe a short distance below the upper end thereof. Above the branches the 30 pipe is perforated as at 11 to form burner orifices. Extending upwardly from each of the arms or branches 10 is a pipe or tube 12, connected by a bend 13 at the top to a downwardly extending part 14, which terminates 35 at an open nozzle, at 15, located under the branch 10 and directed toward the main pipe 7. The ends of the pipe 7 and its branches 10 are closed by plugs or caps.

In the use of the burner, the generation is 40 started by opening the valve 8 and allowing a small quantity of the oil to flow out the holes 11 and down into the pan 9. This oil is then lighted and will heat the oil in the head of the burner sufficiently to vaporize 45 the same. The pressure incident to the vaporization causes the gas to flow up through the pipes 12 and thence down through the pipes 14 to the burner openings 15 where, in due time, it will ignite and continue the

generation and combustion. The heat will 50 speedily fill the burner head and the loops with gas, which will thus burn at the orifices 11 as well as at the nozzles 15.

The loops 12, 13 and 14 serve to form a chamber of sufficient size to contain the gas 55 generated, and inasmuch as the heat is concentrated from the nozzles 15 against the head of the pipe the oil is vaporized as fast as it is fed thereto, the heat at the T being very intense, so that after initial generation oil 60 will very rarely appear, and if it does escape it will simply flow out of the openings 11 and into the pan where it will be consumed. Necessarily no oil can flow up through the loops, since it will not rise therein any higher 65 than the orifices 11, but the gas generated, being in much larger volume, will readily flow around the loops to the main nozzles. Although the device is shown with two loops, it may be operated with one. 70

I claim:

1. A burner comprising a supply pipe having external ignition jet holes at the upper end, and a looped tube extending upwardly from the pipe and returned downwardly and 75 having a burner nozzle directed toward the same below said holes.

2. A burner comprising an upwardly projecting supply pipe having a laterally extending branch pipe, and external ignition 80 jet holes, and a looped tube extending upwardly from said branch and above the jet holes, and terminating in a nozzle under said branch.

3. A burner comprising an upwardly projecting pipe having a T head and external ignition jet holes above said head, and looped tubes extending upwardly from said branches, above the level of the jet holes, and then downwardly, and terminating in 90 nozzles under said branches and directed toward the pipe. 85

In testimony whereof I affix my signature, in presence of two witnesses.

LEVI B. BULLINGTON.

Witnesses:
